UNITED STATES PATENT OFFICE

2,460,731

CRANKPIN GRINDING APPARATUS

Albert G. Belden and Carl G. Flygare, Worcester, Mass., assignors to Norton Company, Worcester, Mass., a corporation of Massachusetts

Application May 21, 1947, Serial No. 749,414

6 Claims. (Cl. 51—72)

1

The invention relates to grinding machines, and more particularly to a crankpin grinding machine.

One object of the invention is to provide a simple and thoroughly practical crankpin grinding machine. Another object is to provide a crankpin grinding attachment for a standard cylindrical grinding machine. Another object of the invention is to provide a crankshaft supporting chuck adapted for use on cylindrical grinding machine. Another object is to provide a crankshaft supporting chuck which is arranged to be drivingly supported on the headstock of a cylindrical grinding machine. A further object is to provide a crankshaft supporting chuck, one end of which is yieldably supported on the headstock and the other end of which is supported by a steadyrest. Other objects will be in part obvious or in part pointed out hereinafter.

The invention accordingly consists in the features of construction, combinations of elements, and arrangements of parts, as will be exemplified in the structure to be hereinafter described, and the scope of the application of which will be indicated in the following claims.

One embodiment of the invention has been illustrated in the accompanying drawings, in which like reference numerals indicate like parts and wherein:

Fig. 1 is a front view of a cylindrical grinding machine embodying the invention;

Fig. 2 is a vertical sectional view, on an enlarged scale, through the crankshaft supporting chuck, showing the chuck drivingly and yieldably supported on the headstock center;

Fig. 3 is a right hand end elevation of the chuck; and

Fig. 4 is an end elevation of the crankshaft supporting chuck, showing the steadyrest support for the end portion of the chuck.

A cylindrical grinding machine is illustrated in the drawings comprising a base 10 which serves as a support for a longitudinally reciprocable work table 11. The table 11 supports a headstock

12. A rotatable grinding wheel 15 is mounted on the left hand end of a wheel spindle 16. The spindle is rotatably journaled in bearings (not shown) in a transversely movable wheel slide 17. A grinding wheel driving mechanism is provided comprising an electric motor 18 mounted on the upper surface of the wheel slide 16. The motor 18 is provided with a driving pulley 19 which is connected by means of a belt 20 with a pulley 21 on the right hand end of the spindle 16.

The grinding wheel 15 and slide 17 may be fed transversely relative to the base 10 by means of

2

a feeding mechanism including a manually operable feed wheel 22. The feed wheel 22 is connected to rotate a gear 23 which is mounted on the forward end of a feed screw shaft 24. The shaft 24 serves to rotate a feed screw (not shown) which meshes with a half nut (not shown) depending from the underside of the wheel slide 17. It will be readily apparent from the foregoing disclosure that a manual rotation of the feed wheel 22 will impart a transverse movement to the wheel slide 17 and the grinding wheel 15. The grinding wheel 15 may be fed automatically by means of a pawl 25 which is arranged to engage teeth on the periphery of the feed wheel 22. A hydraulically operated actuating motor contained in the case 26 which is controlled by a table reversing lever 27 is provided to actuate the pawl 25 automatically during reversal of the table 11 at the ends of its reciprocatory stroke. This mechanism has not been shown in detail since it is not considered to be a part of the present invention. This mechanism is substantially identical to that shown in the prior United States Patent No. 2,071,677 to W. H. Wood dated February 23, 1937 to which reference may be had for details of disclosure not contained herein.

A manually operable table traverse mechanism is provided to facilitate positioning the table relative to the grinding wheel 15. This mechanism may comprise a manually operable traverse wheel 28 which is mounted on the outer end of a shaft 29. The shaft 29 supports a gear 30 which meshes with a gear 31. The gear 31 is mounted on a rotatable shaft (not shown) which also supports a gear 32. The gear 32 meshes with a rack bar 33 which is fixedly mounted on the underside of the table 11. It will be readily apparent from the foregoing disclosure that a rotary motion of the manually operable traverse wheel 28 is imparted to cause a longitudinal traversing movement of the table 11. The direction of rotation of the wheel 28 determines the direction of movement of the table 11.

A power operated mechanism is provided for traversing or reciprocating the table longitudinally comprising a hydraulic cylinder 35 which is fixedly mounted on the underside of the table 11. The cylinder 35 contains a pair of spaced pistons (not shown) which are connected by means of hollow piston rods 36 and 38 with hollow brackets 37 and 39 respectively. The brackets 37 and 39 are fastened to the ends of the base 10. A reversing and control valve unit 40 is provided which is connected with pipes 41 and 42 with the brackets 37 and 39 respectively to convey fluid

under pressure to and from opposite ends of the cylinder 35. The table actuated reversing lever 21 serves to actuate the reversing valve. A start and stop lever 43 is provided to actuate a start-stop and speed control valve contained in the valve unit 40. This hydraulic table reciprocating mechanism is identical with that disclosed in the prior U. S. Patent to Wood No. 2,071,677 to which reference may be had for details of disclosure not contained herein.

The headstock 12 is provided with the usual work supporting center 46 and a rotatable face or driving plate 45.

In order to attain the main object of the invention, a crankshaft supporting chuck 47 is provided which may be readily applied to a standard cylindrical grinding machine for grinding crankpins. The chuck 47 is arranged to support a crankshaft so that the crankpin to be ground may be positioned in axial alignment with the axis of rotation of the chuck. The left hand end of the chuck 47 is provided with a center bushing 48 which mates with the headstock center 46.

The face or driving plate 45 supports a pair of diametrically opposed driving studs or bolts 49 and 50. The bolts 49 and 50 are provided with integral heads 51 and 52 respectively which are supported in a diametrically opposed radially-extending T-shaped slots 53 and 54 respectively formed in the face plate 45. Locking nuts 55 and 56 are provided to lock the bolts 49 and 50 respectively in adjusted positions relative to the plate 45. The driving bolts 49 and 50 pass through clearance holes 57 and 58 respectively formed in a flange 59 which is an integral part of the chuck 47. A pair of compression springs 60 and 61 surround the bolts 49 and 50 respectively and are interposed between the flange 59 and nuts 62 and 63. The springs 60 and 61 serve yieldably to support and maintain the chuck 47 with the center bushing 48 in engagement with the headstock center 46.

The main body portion of the chuck 47 is formed with a true cylindrical peripheral surface, the right hand end of which is support for rotation by means of a steadyrest 65. The steadyrest 65 is adjustably clamped on the work table 11 and is provided with a pair of adjustably mounted steadyrest shoes 66 and 67 which engage and support the periphery of the chuck 47. The shoes 66 and 67 may be adjusted by means of the usual adjusting screws 68 and 69 respectively. A bracket 70 is either formed integral with or fixedly mounted on the steadyrest 65. The bracket 70 serves as a support for a shoe 71 which engages the upper portion of the chuck 47, thus forming a three point support for the right hand end of the chuck 47. An adjusting screw 72 is provided to facilitate adjustment of the shoe 71 relative to the bracket 70.

The chuck 47 is provided with a longitudinally extending cylindrical aperture 75, the axis of which is parallel to the axis of rotation of the chuck. The axis of the aperture 75 is spaced from the axis of rotation of the chuck 47 by a distance equal to the throw of the crankpin to be ground. A split bushing 76 is mounted in the right hand end of the aperture 75. The bushing 76 is provided with a central aperture 77 which mates with the main bearing portion of a crankshaft 78. A clamping mechanism is provided for clamping the bushing 76 to clamp the crankshaft 78 in the chuck 47 during a grinding operation. The clamping mechanism comprises a

clamping screw 80 which passes through a clearance hole in a bushing 81 and is screw threaded into a bushing 82. The bushings 81 and 82 are supported in a transversely extending hole 83 formed in the chuck 47 (Fig. 3). The bushings 81 and 82 are provided with surfaces 84 and 85 which engage and mate with the outer peripheral surface of the split bushing 76. It will be readily apparent from the foregoing disclosure that tightening the clamping screw 80 will draw the bushings 81 and 82 towards each other to clamp the split bushing 76 and the crankshaft 78 to be ground in the chuck 47. Before clamping the crankshaft 78 is rotarily adjusted so that the axis of a crankpin 79 to be ground is aligned with the axis of rotation of the chuck 47.

In order to steady the crankshaft 78 during a grinding operation, a slidably mounted center 85 is provided which engages a center hole 84 formed in the end of the crankshaft 78. The center 85 is formed integral with a slidably mounted member 86 which slides within the aperture 75. A compression spring 87 which is interposed between the member 86 and an end cap 89 serves yieldably to maintain the center 85 in engagement with the center hole 84.

The operation of the improved crankpin grinding attachment will be readily apparent from the foregoing disclosure. The crankshaft supporting chuck 47 is mounted as illustrated in Fig. 2 with the center bushing yieldably maintained in engagement with the center 46. The other end of the chuck is supported and steadied by the shoes 66, 67 and 71 of the steadyrest 65. The chuck 47 is driven by the face plate 45 by means of the driving studs or bolts 49 and 50. A crankshaft 78 to be ground is inserted within the split bushing 76 and moved axially until the center hole 84 engages the center 85 and moves the supporting member 86 toward the left (Fig. 2) to compress the spring 87. The crankshaft 78 is then rotated within the split bushing 76 until the crank arm 90 (Fig. 2) engages a locating stop 91 (Fig. 3) to position the crankpin 79 to be ground in axial alignment with the axis of rotation of the chuck 47. The clamping screw 80 is then tightened to clamp the crankshaft 78 in the chuck 47 for a grinding operation.

The work table 11 may then be traversed longitudinally to position the crankpin 79 opposite the grinding wheel 15. The chuck 47 may then be rotated and the grinding wheel 15 fed toward the crankpin 79 to grind it to the desired and predetermined size.

It will thus be seen that there has been provided by this invention apparatus in which the various objects hereinabove set forth together with many thoroughly practical advantages are successfully achieved. As many possible embodiments may be made of the above invention and as many changes might be made in the embodiment above set forth, it is to be understood that all matter hereinbefore set forth or shown in the accompanying drawings is to be interpreted as illustrative and not in a limiting sense.

We claim:

1. In a cylindrical grinding machine having a longitudinally movable work table, a headstock on said table having a rotatable face plate and a center, and a crankshaft supporting chuck, yieldable means drivingly to hold one end of said chuck on said center, and a steadyrest on said table rotatably to support the other end of said chuck, said chuck being arranged to support a crankshaft with its axis offset from the axis of

rotation by a distance equal to the throw of the crankpin to be ground.

2. In a cylindrical grinding machine having a longitudinally movable work table, a headstock on said table having a rotatable face plate and a center, and a crankshaft supporting chuck, yieldable means drivingly to hold one end of said chuck on said center, a steadyrest on said table rotatably to support the other end of said chuck, and an offset crankshaft supporting and clamping means on said chuck to support a crankshaft so that the axis of the crankpin to be ground is in alignment with the axis of rotation of the chuck.

3. In a cylindrical grinding machine having a longitudinally movable table, a headstock on said table having a rotatable face plate and a center, and a crankshaft supporting chuck, yieldable means drivingly to hold one end of said chuck on said center, and a steadyrest on said table rotatably to support the other end of said chuck, said chuck having a split bushing to support a crankshaft with the crankpin to be ground in axial alignment with the axis of rotation of said chuck and a binder screw on said chuck to clamp said bushing and crankshaft in said chuck for a grinding operation.

4. In a cylindrical grinding machine having a transversely movable rotatable grinding wheel, a longitudinally movable work table, a headstock having a rotatable face plate and a center which is supported on said table, and a crankshaft supporting attachment including a frame, a center hole in one end of said frame adapted to mate with the headstock center, yieldable means drivingly to hold said frame on said center, a steadyrest to support the other end of said frame, and a crankshaft supporting chuck formed in said frame.

5. In a cylindrical grinding machine having a transversely movable rotatable grinding wheel, a longitudinally movable work table, a headstock having a rotatable face plate and a center which

is supported on said table, and a crankshaft supporting attachment including a cylindrically shaped frame, a center hole in one end of said frame adapted to mate with the headstock center, yieldable means drivingly to hold said frame on said center, a steadyrest having adjustable shoes to support the other end of said frame and a crankshaft supporting chuck formed in said cylindrical frame, the axis of said chuck being offset from the axis of rotation of said frame by a distance equal to the throw of the crankpin to be ground.

5 6. In a grinding machine having a transversely movable rotatable grinding wheel, a longitudinally movable work table, a headstock having a rotatable face plate and center on said table, a crankshaft supporting attachment including a cylindrically shaped frame, yieldable means drivingly to support one end of said attachment frame on said center, a steadyrest on said table having adjustable shoes to support the other end of said frame, an aperture in said frame parallel to the axis of the frame and spaced from said axis by a distance equal to the throw of the crankpin to be ground, a spring pressed center in one end of said aperture to engage and support one end of a crankshaft to be ground, and a crankshaft supporting chuck in said aperture adjacent to the end of said frame to support a crankshaft with the axis of the crankpin to be ground aligned with the axis of rotation of the frame.
